TORCH JIG FOR CIRCULAR WELDING

Frank Guida, 144 Harryel St., Pittsfield, Mass.

Filed Nov. 17, 1960, Ser. No. 62,878

Term of patent 14 years

(Cl. D62—2)

F I G. 2

F I G. 4

FIGURE 1 is a side elevation of a torch jig for circular welding, showing my new design;

FIGURE 2 is a plan view of the same;

FIGURE 3 is a front elevation of the same;

FIGURE 4 is an opposite side elevation of the same;

FIGURE 5 is a rear elevation of the same; and FIGURE 6 is a section on the line 6—6 of FIGURE 1, on a reduced scale.

I claim:

The ornamental design for a torch jig for circular welding, as shown.
